NORMAN ANDERSON, OF DULUTH, MINNESOTA.

METER-ACTUATED CUT-OFF DEVICE.

1,173,080.

Specification of Letters Patent. Patented Feb. 22, 1916.

Application filed January 22, 1915. Serial No. 3,799.

To all whom it may concern:

Be it known that I, NORMAN ANDERSON, a citizen of the United States, and a resident of Duluth, in the county of St. Louis and 5 State of Minnesota, have made certain new and useful Improvements in Meter-Actuated Cut-Off Devices, of which the following is a specification.

My invention is an improvement in meter 10 actuated cut-off devices, and the invention has for its object to provide a device of the character specified, for use in connection with water meters, for automatically delivering fixed and predetermined quantities of 15 water, and wherein the mechanism is so arranged that when it is set in operation, it will deliver a predetermined amount of water, after which the device will automatically shut off the water, and the mechanism is so arranged that the amount of 20 water delivered may be varied.

In the drawings: Figure 1 is a front view of the improved meter, with the parts in meter operating position, Fig. 2 is a section 25 in the plane of the meter, and Fig. 3 is a section on the line 3—3 of Fig. 2, looking in the direction of the arrows adjacent to the line.

The present embodiment of the invention 30 comprises a substantially cylindrical casing composed of a head 1 of circular form, having a marginal lateral flange 2, and another head 3 fitting against the edge of the flange and secured thereto by means of bolts 4, the 35 said bolts being passed through registering perforated bearing lugs 5 on the flange 2, and 6 on the head 3, and the bolts are engaged by nuts 7 to clamp the parts together. A shaft 8 is journaled co-axial of the casing, 40 and a rotor or piston 9 in the shape of a disk is secured to the shaft within the casing, by means of a key 10, the key engaging registering key-ways in the shaft and in the piston. It will be noted from an inspection 45 of Fig. 2 that while the outer or peripheral surface of the flange 2 is cylindrical, the inner surface thereof is not truly cylindrical, there being an eccentric portion 11 within the casing, the said portion providing an 50 abutment for a purpose to be presently described. The rotor or piston 9 is provided with recesses 12, at opposite sides of the center, said recesses being parallel, and extending from the periphery at one side of 55 the disk to near the periphery at the other side. Blades or vanes 13 are arranged with-

in the recesses 12, the outer edges of the vanes being adapted to engage the inner surface of the flange 2, and the vanes are normally pressed outward by coil springs 14 60 which are arranged within the recesses 12, between the bottoms thereof and the inner edges of the blades or vanes. The recesses 12 are parallel with tangents to the disk, and the said recesses extend through the thickness of the disk, so that there is a fluid tight contact between the side edges of the blades and the inner surface of the heads 1 and 3; as well as between the ends of the blades and the inner surface of the flange 2. At 70 the abutment 11 the flange 2 is provided with passages 15 and 16, extending through the flange, from the interior of the casing to the exterior, and a valve casing 17 is secured to the flange 2 at the passage 15. This valve 75 casing 17 is formed at one side to fit smoothly against the periphery of the flange and at the said side the casing has perforated lugs 18 through which are passed set screws 19, the said screws engaging 80 threaded openings in the flange to secure the casing in place. The casing has a central cylindrical bore 20 parallel with the axis of the shaft 8, and a passage 21 leading radially from the bore, and registering with 85 the outer end of the passage 15. A cylindrical tubular valve 22 is journaled to rotate in the casing, and the valve has a radial port 23 adapted to register with the port or passage 21 of the casing. A pipe 24 is connected to one end of the casing 22, and the other end is closed, as shown in Fig. 1.

A pipe section 25 is arranged at the port or passage 16, the said pipe section having a flange 26 which fits against the periphery of 95 the flange 2, and is secured thereto by means of set screws 27, the said screws passing through openings in the flange 2. Outside of the head 3 a radial arm 28 is secured to the valve casing 22 for a purpose to be presently described, and it will be evident that when the arm 28 is moved in the proper direction the port or passage 23 of the valve will be moved into and out of register with the port or passage 21. A stub shaft 29 is 100 journaled in the head 3 of the casing between the shaft 8 and the pipe 25, and a ratchet wheel 30 is journaled on the shaft outside of the head. A wheel 31 is secured to the shaft 8 outside of the head 3, and the 110 said wheel is provided with a single tooth 32 for engaging the teeth of the ratchet wheel

30. A holding pawl 33 is pivoted on the outer face of the head 3 adjacent to the ratchet wheel 30, as indicated at 34, and one end of the pawl engages the ratchet wheel, 5 the other end having a weight 35 acting normally to hold the opposite end of the pawl in engagement with the ratchet wheel. A lever is pivoted on one of the bolts 4, the said lever consisting of portions 36 and 36^a 10 straight and approximately parallel but offset laterally with respect to each other and connected by an arc-shaped portion 36^b. The portion 36 of the lever is pivoted to a bolt 4 adjacent to the valve casing 17, and at 15 the junction of the portion 36 with the portion 36^b a link is pivoted to the lever at one end of the link. The link is angular as shown, consisting of portions 37 and 37^a extending at an obtuse angle with respect to 20 each other and at the junction of the portions the arm 28 is pivoted to the link. The arm 28 is thus held almost parallel with the portion 36 of the lever. A plate spring 38 is connected at one end to a pin 39 on the portion 36^b of the lever, and the other end of 25 the spring bears against the lug 6 of the bolt 4 to which the portion 36^b of the lever is pivoted. The outer end of the portion 36^a of the lever has an eye or opening 40, and 30 one end of a flexible member 41, a chain in the present instance, is engaged with the eye or opening. The lever at the portion 36^a is provided with a tooth or catch 42, and one end of a pawl 43 pivoted at 44 on the head 3 35 engages the tooth. The pawl is angular, or an elbow lever, and a weight 45 is so arranged on the pawl that it will hold the pawl normally in engagement with the tooth or catch 42 of the lever. A coil spring 46 is 40 arranged between the ratchet wheel 30 and the stub shaft 29, one end of the spring being connected to the pin 47 on the ratchet wheel, while the other end is engaged with a kerf or notch in the shaft, as indicated at 45 48. The spring 46 normally holds the stub shaft and the ratchet wheel in a predetermined position with respect to each other, and when the ratchet wheel is moved angularly with respect to the stub shaft, the 50 spring will return the parts to normal position.

It will be noted that the inner surface of the abutment 11 is so arranged that it will gradually move the blades or vanes 13 inwardly into the recesses 12, as the said blades or vanes travel over the said abutment, and will permit the said blades or vanes to be extended from the recesses by the coil springs 14, as soon as they pass off 55 from the abutment. The exhaust port 16 is arranged at the point where the blades or vanes are almost completely pushed into their recesses by the abutment, while the inlet 15 is at the point where the blades or 60 vanes pass off from the abutment. The disk 65

9 fits the casing closely at its opposite sides, and the periphery thereof moves in close engagement with the interior of the abutment 11, to form a fluid tight joint at this point. Since the disk is of less diameter than the 70 internal diameter of the casing, a chamber of arc-shape is formed between the disk and the casing, the said chamber extending from one end of the abutment to the other, that is, from the inlet to the outlet. The normal 75 position of the parts is, as shown in Fig. 1, with the outlet 16 below. When the valve 22 is closed the lever 36-36^a is lifted at its free end, and is out of engagement with the pawl 43. The lifting of the lever causes the 80 cam 37^a to release the pawl 33 from the ratchet wheel 30. The spring 38 holds the lever lifted.

The operation of the device is as follows: It will be understood that in practice the 85 parts shown on the face of the casing in Fig. 1 are covered, so that access thereto may not be had by unauthorized parties. The position of the pin 50 determines the amount of water that will be delivered, and it will be 90 understood that the pin 50 is placed in that opening 51 which will permit the pin to stop the operation when the requisite amount of water has been delivered. With the parts 95 so arranged, when the lever 36^a is pulled downward, by the chain 41, the tooth 42 engages the pawl 43, and holds the lever in lowered position. The movement of the lever causes the cam 37^a to release the pawl 33, which immediately engages the teeth of the 100 ratchet wheel 30. The movement of the lever 36^a also opens the valve 22, and the flowing water drives the mechanism 9-13. At each rotation of the rotor, 9-13, the ratchet wheel 30 will be rotated a distance of one 105 tooth, and the pawl 33 will hold it from reverse rotation. The pin 50 will, when the requisite amount of water has passed, that is, when the rotor has turned a predetermined number of times, strike the pawl 43 110 and will disengage it from the tooth 42 of the lever 36^a, and the spring 38 will immediately force the lever upward, closing the valve 22. The cam 37^a on the upward movement of the lever will disengage the 115 pawl 33 from the ratchet wheel, and the spring 46 will return the ratchet wheel to original position. The pawl 33 is out of engagement with the ratchet wheel 30 when the lever 36^a is in upward position, that is, 120 when the valve 22 is closed. The cam 37^a releases the pawl as soon as the lever is depressed, so that it can engage the ratchet wheel.

Every time the lever 36^a is pulled downward and engaged with the pawl 43 the rotor will rotate until it has moved the ratchet wheel 30 a distance sufficient to cause the pin 50 to operate the pawl 43 to release the lever 36-36^a. As long as the pin 50 remains in 130

one opening the device will deliver the same amount of water whenever it is operated, and the amount of water delivered may be varied by engaging the pin with different 5 openings. The blades or vanes form a fluid tight joint transversely of this passage, when they are extended. It will be evident that when the valve 22 is operated to admit water by way of the passages 15 and 21 the entering 10 water engaging the blade or valve adjacent thereto will drive the said blade or vane forwardly, thus rotating the disk or rotor 9. This rotation of the disk will continue until the blade or vane passes the outlet 16 from 15 the casing. As soon as the blade or vane passes the outlet the water will discharge, and since at the time when a blade or vane passes the outlet 16 the other blade or vane is directly above the said outlet, all of 20 the water between the blades or vanes will run out by gravity if it were not forced out by the succeeding vanes. As each blade or vane passes the abutment the water entering by the inlet 15 impinges against the said blade 25 or vane pressing it forward and rotating the rotor 9. Thus water will be discharged from the outlet 16, so long as water is permitted to enter by the inlet 15. As long, however, as the tooth 32 which is rigid with 30 the disk 9 is locked by its engagement with the teeth of the ratchet wheel 30, which in turn is locked by the pawl 33, it cannot turn, and the ratchet wheel must be released before the disk can turn. When the lever 35 36^a—36^b is operated by the chain 41, that is, when the free end of the said lever is depressed, the valve 22 is operated to admit water to the casing by way of the inlet 15.

I claim:

40 1. A device of the character specified, comprising in combination with a rotating water meter having an inlet and an outlet, and a valve for controlling the inlet, said valve being rotatable, an arm connected with 45 the valve for operating the same, a lever pivoted to the meter casing and connected with

the arm for opening the valve when the lever is depressed, a normally operative pawl for holding the lever in depressed position, a toothed wheel connected with the meter 50 and rotated thereby, a ratchet wheel engaged by the toothed wheel for moving the ratchet wheel a distance of one tooth for every complete rotation of the meter, a spring for returning the ratchet wheel to 55 original position, a normally operative pawl for holding the wheel from reverse movement when it is moved by the meter, means operated by the lever when it is lifted for releasing the last named pawl, said ratchet 60 wheel having a series of radial openings, and a pin for engaging one of the openings and extending beyond the periphery of the ratchet wheel to engage the first named pawl to release the same when the pin passes the 65 said pawl, and a spring for returning the lever to normal position.

2. A device of the character specified, comprising in combination with a rotating water meter having an inlet and an outlet, a 70 valve controlling the inlet, said valve being rotatable, an arm secured to the valve for operating the same, a ratchet wheel, a connection between the said wheel and the meter for moving the wheel a distance of one tooth 75 for each complete rotation of the wheel, a normally operative pawl for holding the wheel from reverse rotation during its movement by the meter, a common means for opening and closing the valve and for releasing the said pawl when the valve is closed, 80 releasable means for holding the said valve operating means with the valve open, means adjustable with respect to the ratchet wheel for releasing said pawl, and a spring in connection with the said valve opening means for closing the valve when the said means is released from the pawl.

NORMAN ANDERSON.
